FOLDING DOOR CONSTRUCTION

Clark D. Michael, Claude A. Morgan, and Will D. Redrup, Huntington, Ind., assignors to The Majestic Company, Huntington, Ind., a corporation

Application November 13, 1931, Serial No. 574,716

13 Claims. (Cl. 20—20)

This invention relates to a sectional door which is of the rolling and folding type.

The chief object of this invention is to produce a door of the general character indicated which requires but little manual effort to elevate or lower and which is constrained toward the open position and normally retained in closed position, whereby upon release from the retaining arrangement, the door is substantially automatically opened.

One feature of the invention in addition to the accomplishment of the foregoing object, consists in the arrangement of the several sections and the addition of means thereto, so that in the movement of the upper section rearwardly from the door opening, the second section is constrained toward folded position.

Another feature of the invention consists in the particular retaining means associated with the door and door casing which may be of the manually controlled, mechanically actuated or electrically actuated type and which may be of the slide bolt and/or tiltable catch type.

Another feature of the invention consists in the mounting arrangement for the counterbalancing provided and more specifically, in the provision for mounting the flexible connection between the counterbalancing and the door upon a pulley and its retention upon said pulley.

Another feature of the invention consists in the arrangement of parts permitting rapid and ready mounting of the door in the vertical guides.

Still, a further feature of the invention consists in the means for maintaining the guides in parallelism.

The full nature of the invention will be understood from the accompanying drawings and the following claims and description:

In the drawings, Fig. 1 is a side elevation of the door and one side guide structure, and associated parts, the door being shown in the door closing position.

Fig. 2 is a similar view of the upper portion of the guide structure with the door in the overhead and folded position.

Fig. 3 is a top plan view of the door and guide structure.

Fig. 4 is an enlarged transverse sectional view and is taken on line 4—4 of Fig. 1 and in the direction of the arrows.

Fig. 5 is an elevational view of the adjustable mounting of the uppermost guide wheel supporting member.

Fig. 6 is a side elevation of one edge of the

door and the restraining mechanism applied thereto, a portion being shown in section to illustrate other parts in detail.

Fig. 7 is a front view of the manual and key actuated portions of a portion of the restraining mechanism.

Fig. 8 is a rear view of the same.

Fig. 9 is a semi-diagrammatic illustration of a modified form of restraining mechanism, the remote and electric control being shown diagrammatically, certain parts being shown in section and others in side elevation.

In the drawings, there is illustrated a pair of substantially vertical upwardly directed guide or trackway structures 10, the same being oppositely directed and positioned at opposite sides of the door and including a face 11 and an opposite face 12, the guide being of substantially channel arrangement. One of said face structures has an inturned flange 13 which, near the lower portion, is cut away or relieved as at 14, for the purpose hereinafter set forth. The side jamb 15 covers a weight box arrangement in which is mounted a long but smaller cross sectional weight 16 and a smaller but larger cross sectional weight 17. The two are maintained in separated relation by a suitable partition 18 of sound-deadening material and the like, and such a partition has been found satisfactory when made of what is known in the trade as Celotex or equivalent material, this being a wood fiber composition board.

Herein the door structure is illustrated as comprised of three sections. The door structure may be comprised of five sections, whenever required, and these may be of equal or unequal length or depth. All the sections herein, however, have substantially the same width. Herein the bottom section is indicated by the numeral 19, the intermediate section by the numeral 20, and the upper section by the numeral 21. Sections 20 and 21 are hingedly connected together as at 22. Sections 19 and 20 are hingedly connected together as at 23. The hinge pin 22a is elongated and mounts a guide wheel 24 that is receivable by the upwardly directed track or guide. The wheel 24—see Fig. 4—is mounted in the track or guide by being passed transversely through the slot or opening 14 in the flange 13. The section 20 is then elevated. The section 19 is also elevated and has its lower edge moved forwardly until the guide wheel 25 is in transverse alignment with the same opening 14, whereupon the pintle 25a thereof is projected axially and through the slot and the wheel is positioned in the vertical guide, as indicated in Fig. 4. During this mounting of the door in the

vertical guides, the upper section may hang downwardly and rearwardly if desired.

After the two lower sections, and any succeeding sections if more than three and an odd number are utilized, are mounted in the vertical guides, the guide wheel 26 is mounted in the projecting end 28 of an angular bracket member 29, adjustably secured at each upper edge of the door as at 29a—see Fig. 5. The guide wheel 26 may be readily mounted in the rearwardly directed and substantially horizontally positioned track 30 which terminates in abutting relation to the vertical or upwardly directed track 10—see particularly Figs. 1 and 2.

As shown clearly in Figs. 1 and 3, the rearward and free ends of the horizontal tracks 30 which are channel shaped and are oppositely directed, are connected by the spacing and bracing member 31.

A coil spring 27 is suitably secured as at 32 to the upper edge of the upper door section at an appreciable distance in from the side edge thereof and the opposite end of the spring is secured at the rearward end of the rearwardly directed guide 30 and to the cross member 31 as at 33. The reason for this so-called angular or diagonal positioning is clearly evident from an examination of Fig. 3, wherein the dotted line indicating the spring 27 in its final position illustrates that the spring is of greater length than the perpendicular distance between the upper edge of the upper door section when elevated and the cross member 13 or the end of the horizontal guide 30. With this arrangement, therefore, greater spring strength and greater length of spring may be obtained and utilized respectively.

As the upper door section has its upper edge moved rearwardly by reason of wheels 26 moving rearwardly in the horizontal tracks 30, the lower edge of said door section moves upwardly which carries with it all of the lower sections. The same are hingedly connected end to end. In this elevational movement and rearward movement of the upper door section, a pair of springs 34 positioned at opposite sides of the door and secured at one end, as at 35, to the upper door section and to the next lower door section at its opposite end 36, has its upper ends moved rearwardly, as indicated in Fig. 2, and said springs assist in the elevational movement of the second section and the lower section or sections and also assist in breaking the door at the hinged joint and secure the automatic folding of the sections.

A counterbalancing structure comprises a cable 37 secured as at 38 to the lower portion of the lower door section at a point a considerable distance above the bottom of the door so as to obtain additional weight travel and said cable 37 is directed upwardly and rearwardly passing over a guide pulley 39 and is connected at its opposite end to the weight 17 as at 40. Herein the lower end of the upper door section is connected to the flexible cable 41 and said cable passes over the guide pulley 42 and is connected as at 43 to the long weight 16.

The counterbalancing and springs associated with the door are of such a character that when the door is released from its locking means or restriction, it automatically moves from the closed position to the overhead and open position. To cushion the shock, there is provided at the upper end of the upwardly directed guide 10, a rubber or cushioned bumper 44. To insure substantially initial vertical and upward travel of the lower sections of the door in the initial opening move-

ment of the door, the guide springs 45 bear upon the cam guide member 46 mounted upon the side jamb or weight housing. As soon as spring 45 leaves the cam portion 46, the section 19 starts to fold relative to the section 28 so that the movement of the door is initially rearward for the upper section and upwardly for the lower sections and thence upwardly and foldingly for the lower sections in the continued rearward movement of the upper section.

The flexible cables 41 and 37 are successively positioned in the offset portion 47 of the housing or bracket 48 that supports a shaft 49 that mounts pulleys 42 and 39. The pulleys 41 and 39 are slidably mounted on said shaft, as well as rotatably mounted thereon and are adapted to register with the offset portion 47 for cable mounting. After the cable has been mounted on the pulley, each pulley is shifted axially on the shaft 49.

In Figs. 6 to 9 inclusive, there is illustrated two forms of a lock strike mechanism, the second form being more or less diagrammatically illustrated.

In Figs. 6, 7 and 8, there is illustrated a lock 70 having the cylinder 71 by which a shaft of the lock, of the usual night latch character, is turned. The night latch casing is indicated at 72, the handle indicated at 73, and the bolt by the numeral 74. An outer plate 75 is associated with the lock mechanism—see Figs. 6 and 7—and projecting from the same is a handle 76 which is rigid with the shaft 77—see Fig. 8. Rigid with the shaft 77 upon the inside of the door, is a member 78 including a cam portion 79, a catch portion 81 and an arm portion 82. When the lock is turned, the bolt is released or retracted into the night latch lock casing and the shaft 77 may be turned either from the outside of the door by engaging the handle 76 or from the inside of the door by engaging the arm 82. A stop 83 limits the tilting movement of the shaft 77 in one direction and unless the bolt 74 is retracted, movement in the opposite direction is prevented by said bolt.

After the bolt is retracted either by manually releasing the bolt from within the door by engaging member 73 or from without the door by operating the lock 70, the shaft 77 is tilted either by engaging the arm 82 or by engaging the handle 76 respectively, and this tilting of the shaft 77 draws down upon the chain 84 operatively secured to the shaft. Chain 84 is connected to the arm 85 of a bolt member 86, slidably supported in the casing 87 and normally projected outwardly by the spring 88. The bolt includes a locking face 89 and a cam face 90.

In a housing 91 and pivotally supported at 92 therein, is a cam type catch having the catch portion 93 and the cam portion 94. The housing 91 is supported by the adjacent jamb structure 60 and the bolt is carried by the upper door section. As the upper door section rolls toward the jamb and downwardly, the cam face 90 engages cam face 94 of the catch and the bolt 86 is forced downwardly until it rides beneath the catch and then the spring 88 seats it upwardly with the two opposed faces in engagement. The cam type catch is normally retained in position by a locking lever 95 pivotally supported at 96 in the housing 91 and said lever includes an arm 97 to which is secured a pull cord 98. The lever also includes a seat or notch 99 that co-operates with the portion 100 of the cam catch. Spring 100a is also provided.

A spring 101 normally takes all the strain of

the weight of the accumulated cable 98 from the arm 97, so that there will be no weight on the arm 97, and, therefore, no tendency to tilt the lever 95 by reason of the weight of the parts associated with the cable 98 or the weight thereof. Due to the tendency of the door to open by reason of the two upper springs immediately upon release of the catch, which is also movable as well as the bolt, the door starts to open so that when the lever, which operates in a way as a lock for the cam catch, is tilted clockwise and the cam catch is freed therefrom, then the door can tilt the cam catch counterclockwise and thus the bolt 86 acts as the catch and the catch acts as the bolt. This release of the catch is effected by pulling upon the cord 99 from any desired location to which the cord extends or to which any branch of a multiple cord connection is extended.

In Fig. 9 there is illustrated a modified form of the invention and herein similar parts are indicated by like numerals increased by one hundred.

In addition to the pull cord 198 being utilized, there is substituted a link member 202, which terminates in an armature 110. Solenoid 111, when energized, causes armature 110 to register with core 112 and in so doing, the lever lock is released and the cam catch may be tilted by the door springs tending to open the door and in this instance, the tiltable catch constitutes the bolt, while the slidable bolt constitutes the catch.

The solenoid 111 has one terminal connected to the line 113 and the other terminal connected to a line 114. Line 114 is connected by one branch 115 to a switch 116, in turn connected by a branch 117 to a supply line 118. Another branch 119 from line 114 is connected to a switch 120, the other terminal of which is connected to the branch line 121 in series with the line 118. Current supplied to lines 113 and 118 may be supplied to the solenoid by pressing the push button switch 120 which may be mounted within the garage building, or the like, or may be supplied with energy by switch 116 which is operated or controlled by a key actuated, or other equivalent structure, 123 mechanically connected as at 124 to the switch 116. Usually this lock actuated or controlled switch is mounted upon the door casting and upon the outside thereof.

It will be readily apparent also that the mechanism shown in the lower part of Fig. 6 and in Figs. 7 and 8 may be operatively associated with the arm 185 of the lock bolt.

The invention claimed is:—

1. The combination with an upper jamb member, a sectional door comprised of a plurality of door members hingedly connected end to end, the upper edge of the upper door member of which moves rearwardly, means constraining said edge for said movement, means counterbalancing the door members and constraining the same into folded and overhead relation, and a releasable bolt and catch means interposed between the jamb and the upper door member and arranged to hold said door in closed position until released, and magnet operable means for tilting said bolt and catch means.

2. In combination a pair of upwardly directed opposed guides each including an overlapping spaced flange forming a grooved trackway, said flange being relieved near the bottom to form an opening, a plurality of guide receivable members at each side of the door, a transversely slidable support for each member, and means on the door slidably supporting the support, whereby the door

may be readily mounted in the door guides by successively nesting the superposed members in the trackway by projecting outwardly each member and its support when in registration with the flange opening for progressive door section mounting.

3. In a sectional overhead door construction, the combination of a plurality and odd number of door sections hingedly connected end to end, a pair of opposed rearwardly extending overhead guides, means carried by the upper door section adjacent the upper edge and co-operating with the overhead guides to constrain the movement of the upper edge of the upper door section rearwardly, counterbalancing means connected to the lowest section, and means connecting the rearward ends of the rearwardly directed guides for guide spacing and alignment.

4. In a sectional overhead door construction, the combination of a plurality and odd number of door sections hingedly connected end to end, a pair of opposed rearwardly extending overhead guides, means carried by the upper door section adjacent the upper edge and co-operating with the overhead guides to constrain the movement of the upper edge of the upper door section rearwardly, counterbalancing means connected to the lowest section, and a spring extending from adjacent the rearward end of each rearwardly directed guide to the upper door section near the upper edge thereof.

5. In a sectional overhead door construction, the combination of a plurality and odd number of door sections hingedly connected end to end, a pair of opposed rearwardly extending overhead guides, means carried by the upper door section adjacent the upper edge and co-operating with the overhead guides to constrain the movement of the upper edge of the upper door section rearwardly, counterbalancing means connected to the lowest section, and a spring extending from adjacent the rearward end of each rearwardly directed guide to the upper door section at the upper edge thereof and inwardly an appreciable distance from the side edge thereof.

6. In a sectional overhead door construction, the combination of a plurality and odd number of door sections hingedly connected end to end, a pair of opposed rearwardly extending overhead guides, means carried by the upper door section adjacent the upper edge and co-operating with the overhead guides to constrain the movement of the upper edge of the upper door section rearwardly, counterbalancing means connected to the lowest section, means connecting the rearward ends of the rearwardly directed guides for guide spacing and alignment, and spring means connecting the upper door section near the upper edge to the guide connecting means.

7. A combination sectionalized folding and rolling door comprising a plurality and odd number of door sections hingedly connected together, means arranged to constrain rearwardly the top edge of the top section upon the initial door opening movement, means including vertical guides, wheels and counter-balancing to constrain upwardly the sections upon initial door opening movement, and means separate from the last mentioned means arranged to constrain rearwardly the lower portion of the second section from the top for folding the second section overhead adjacent the top section.

8. A combination sectionalized folding and rolling door comprising a plurality and odd number of door sections hingedly connected, means

- arranged to automatically guide rearwardly the top edge of the top section, means including vertical guides, wheels and counter-balancing arranged to constrain upwardly the several sections, upwardly directed guide means associated with one horizontal edge of each door section, and means arranged to automatically constrain two adjacent door sections into folded relation upon initial door movement.
10. 9. In a sectional overhead door construction, the combination of a plurality and odd number of door sections hingedly connected end to end, a pair of opposed rearwardly extending overhead guides, means carried by the upper door section adjacent the upper edge and co-operating with the overhead guides to constrain the movement of the upper edge of the upper door section rearwardly, counterbalancing means connected to the lowest section, and spring means connecting a superposed odd numbered section to the immediate lower even numbered directly connected section and remote from the connection for breaking and elevational purposes.
15. 10. In a sectional overhead door construction, the combination of a plurality and odd number of door sections hingedly connected end to end, a pair of opposed rearwardly extending overhead guides, means carried by the upper door section adjacent the upper edge and co-operating with the overhead guides to constrain the movement of the upper edge of the upper door section rearwardly, counterbalancing means connected to the lowest section, and spring means connecting a superposed odd numbered section to the immediate lower even numbered directly connected section and remote from the connection for breaking and elevational purposes.
20. 11. In a sectional overhead door construction, the combination of a plurality and odd number of door sections hingedly connected end to end, a pair of opposed rearwardly extending overhead guides, means carried by the upper door section adjacent the upper edge and co-operating with the overhead guides to constrain the movement of the upper edge of the upper door section rearwardly, counterbalancing means connected to the lowest section, and spring means connecting a superposed odd numbered section to the immediate lower even numbered directly connected section and remote from the connection for breaking and elevational purposes.
25. 12. In a sectional overhead door construction, the combination of a plurality and odd number of door sections hingedly connected end to end, a pair of opposed rearwardly extending overhead guides, means carried by the upper door section adjacent the upper edge and co-operating with the overhead guides to constrain the movement of the upper edge of the upper door section rearwardly, counterbalancing means connected to the lowest section, and spring means connecting a superposed odd numbered section to the immediate lower even numbered directly connected section and remote from the connection for breaking and elevational purposes.
30. 13. In a sectional overhead door construction, the combination of a plurality and odd number of door sections hingedly connected end to end, a pair of opposed rearwardly extending overhead guides, means carried by the upper door section adjacent the upper edge and co-operating with the overhead guides to constrain the movement of the upper edge of the upper door section rearwardly, counterbalancing means connected to the lowest section, and spring means connecting a superposed odd numbered section to the immediate lower even numbered directly connected section and remote from the connection for breaking and elevational purposes.
35. 14. In a sectional overhead door construction, the combination of a plurality and odd number of door sections hingedly connected end to end, a pair of opposed rearwardly extending overhead guides, means carried by the upper door section adjacent the upper edge and co-operating with the overhead guides to constrain the movement of the upper edge of the upper door section rearwardly, counterbalancing means connected to the lowest section, and spring means connecting a superposed odd numbered section to the immediate lower even numbered directly connected section and remote from the connection for breaking and elevational purposes.
40. 15. In a sectional overhead door construction, the combination of a plurality and odd number of door sections hingedly connected end to end, a pair of opposed rearwardly extending overhead guides, means carried by the upper door section adjacent the upper edge and co-operating with the overhead guides to constrain the movement of the upper edge of the upper door section rearwardly, counterbalancing means connected to the lowest section, and spring means connecting a superposed odd numbered section to the immediate lower even numbered directly connected section and remote from the connection for breaking and elevational purposes.
